UNITED STATES PATENT OFFICE.

ERNST LINDNER, OF NEW YORK, N. Y.

DESIGN FOR A KEY FOR GAS-COCKS.

SPECIFICATION forming part of Design No. 23,225, dated April 24, 1894.

Application filed June 3, 1893. Serial No. 476,525. Term of patent 7 years.

To all whom it may concern:

Be it known that I, ERNST LINDNER, a citizen of the United States, residing at New York, in the county of New York and State of New York, have invented and produced a new and original Design for a Key for Gas-Cocks, of which the following is a specification, reference being had to the accompanying drawings, forming a part thereof.

In the annexed drawings there is shown a view in elevation of a key for gas-cocks which embodies my new design. The key comprises a plug *a* of the conventional shape and a thumb-piece or handle *b* connected to the head of said plug and whereby the plug is operated.

The particular feature of my design resides in the shape or configuration of the thumb-

piece or handle *b* which, as will be observed, is a flat disk with a central opening through it. The thumb-piece or handle *b* of the described configuration renders the gas-cock key distinctive in appearance and pleasing in its effect upon the eye.

Having thus described my invention, what I claim as new, and desire to secure by Letters Patent, is—

The design for a key for gas-cocks substantially as herein described and shown.

Signed at New York, N. Y., this 26th day of May, 1893.

ERNST LINDNER.
